UNITED STATES PATENT OFFICE.

GEORG RUDOLF BEHRENS SØRENSEN, OF OFOTEN, NORWAY.

VIBRATING SIEVE.

Application filed August 16, 1923. Serial No. 657,774.

This invention relates to vibrating sieves of the kind in which the sieve cloth or plate is connected with an eccentric driving shaft. It is mainly characterized by the feature 8 that the sieve cloth or plate is carried by the driving shaft in bearings which are fixed to the carrier frame of the sieve or plate, whereby the carrier frame is vibrated directly from the shaft and complicated intermediate fittings are eliminated.

The sieve may be adjustably mounted in an inclined plane so that its inclination can be altered to suit the nature of the material to be sifted.

15 In one construction hereinafter more fully described with reference to the appended drawing the sieve cloth or plate is attached to the carrier frame by tensioning screws in such manner that a space is left in the frame 20 for the passage of material which will not pass through the sieve cloth or plate, and the carrier frame is attached by bolts to a rigid outer frame with the interposition of spring means. The outer frame is pivotally mounted at one end and rests at the other end on adjustable supports.

On the drawing, Fig. 1 is a side view of the sieve, Fig. 2 is a plan thereof and Fig. 3 shows diagrammatically (and partly in 25 section) one arrangement of the sieve.

Figure 4 is a detail transverse section showing the eccentrics and their connections for imparting vibratory motion to the sieve.

Figure 5 is a vertical sectional view partly 35 in elevation showing a support for the lower end of the frame.

As illustrated, the sieve cloth or the sieve plate 1 is attached to the carrier frame 2 by tensioning screws 3 so as to leave a passage 40 between one end of the frame and the sieve cloth or plate for the material which will not go through the latter.

The carrier frame 2 is movably mounted within an outer stationary frame 4 by bolts 45 5 on which are springs 6 between the frame 4 and pressure plates held on the bolts by means of nuts.

9 is the operating shaft mounted in bearings 10, 10 on the outer frame 4. The part 50 of this shaft between the end journals is eccentric with respect to said journals and is mounted in bearings 11, 11 on the carrier frame 2 of the sieve cloth or plate 1, so that the frame together with the sieve cloth or plate receives a vibratory motion as the shaft 55 rotates.

The eccentric shaft may be driven as shown in the drawing, through the medium of a belt pulley, fixed thereon outside one of the bearings 10, a loose pulley being fitted 60 alongside the driving pulley in order to interrupt the drive, when required.

In Fig. 3 the sieve is shown mounted in an inclined plane, the upper end of the frame 4 being turnably supported on a shaft 65 7 and its lower end resting on adjustable supports 8, whereby the inclination of the sieve can be varied to suit requirements. A funnel or chute 12 is fitted below the sieve cloth or plate and serves to collect and carry 70 away the material that passes through the latter, while the coarser material passes through a channel or chute 13 below the space left between the sieve cloth or plate and one end of the frame 2.

75 A sieve as herein described can be used for sifting various materials but it will be found particularly suitable for use in sifting or screening ores and minerals.

Having now particularly described and ascertained the nature of my said invention and in what manner the same is to be performed, I declare that which I claim is:

1. In a vibrating sieve, a stationary frame, bearings on said frame, a carrier frame, a sieve element within the carrier frame, bearings mounted on the carrier frame midway between its ends so as to support the frame nearly in its position of equilibrium, a transverse driving shaft having an eccentric portion mounted in the bearings of the carrier frame and its ends mounted in the bearings of the stationary frame, guiding bolts mounted between the carrier frame and the stationary frame so as to be capable of a tilting movement in planes perpendicularly to the plane of the sieve element, and tensioning elements acting upon said bolts so as to maintain the carrier frame yieldingly in connection with the stationary frame during the vibration caused by the eccentric shaft portion.

2. In a vibrating sieve, a stationary frame, bearings on said frame, a carrier frame, a sieve element within the carrier frame, bearings mounted on the carrier frame midway between its ends so as to support the frame nearly in its position of equilibrium, a transverse driving shaft having an eccentric portion mounted in the bearings of the carrier frame and its ends mounted in the bearings of the stationary frame, longitudinal guid-

ing bolts mounted between the carrier frame and the stationary frame so as to be capable of a tilting movement in longitudinal planes perpendicularly to the plane of the sieve element, and tensioning elements acting upon said bolts so as to maintain the carrier frame yieldingly in connection with the stationary frame during the vibrations caused by the eccentric shaft portion.

10 3. In a vibrating sieve, an outer stationary frame, bearings on said frame, an inner carrier frame, a sieve element within the carrier frame, bearings mounted on the carrier frame midway between its ends so as to support the frame nearly in its position of equilibrium, a transverse driving shaft having an eccentric portion mounted in the bearings of the carrier frame and its ends mounted in the bearings on the stationary frame, guiding bolts mounted between the carrier frame and the stationary frame so as to be capable of a tilting movement in planes perpendicular to the plane of the sieve element, pressure plates held on the outer end 20 of the bolts outside the stationary frame, and a compression spring surrounding each bolt between said stationary frame and said plate so as to maintain the carrier frame 25 yieldingly in connection with the stationary frame during the vibrations caused by the eccentric shaft portion.

35 4. In a vibrating sieve, an outer stationary frame, bearings on said frame, an inner carrier frame, a sieve element within the carrier frame so arranged as to provide a space between the carrier frame and the sieve element at its outlet end, bearings mounted on the carrier frame midway between its ends so as to support the frame
40 nearly in its position of equilibrium, a transverse driving shaft having an eccentric portion mounted in the bearings of the carrier frame and its ends mounted in the bearings

of the stationary frame, guiding bolts mounted between the carrier frame and the 45 stationary frame so as to be capable of a tilting movement in planes perpendicular to the plane of the sieve element, pressure plates held on the outer end of the bolts outside the stationary frame, and a compression spring surrounding each bolt between said stationary frame and said plate so as to maintain the carrier frame yieldingly in connection with the stationary frame during the vibrations caused by the eccentric 50 shaft portion.

5. In a vibrating sieve, an outer stationary frame, bearings on said frame, an inner carrier frame, a sieve element within the carrier frame so arranged as to provide a space 60 between the carrier frame and the sieve element at its outlet end, tensioning screws attached at the opposite end of the sieve element and passing adjustably through the corresponding end of the carrier frame, 65 bearings mounted on the carrier frame midway between its ends so as to support the frame nearly in its position of equilibrium, a transverse driving shaft having an eccentric portion mounted in the bearings of the 70 carrier frame and its ends mounted in the bearings of the stationary frame, guiding bolts mounted between the carrier frame and the stationary frame so as to be capable of a tilting movement in planes perpendicular 75 to the plane of the sieve element, pressure plates held on the outer end of the bolts outside the stationary frame and a compression spring surrounding each bolt between said stationary frame and said plate so as to maintain the carrier frame yieldingly in 80 connection with the stationary frame during the vibrations caused by the eccentric shaft portion.

In witness whereof I affix my signature.
GEORG RUDOLF BEHRENS SØRENSEN.
